SEAM TAPING MACHINE

Philip L. O'Donnell, Norwood, Ohio

Application July 3, 1929, Serial No. 375,796

5 Claims. (Cl. 154—42)

This invention relates to tape applying machines and especially to that class of taping machines by means of which tape is rendered adhesive and applied to the seams of shoes of various kinds.

Another object is to provide a device of this character which is especially adapted to apply tape, smoothly and without puckering, to seams having a compound curve such as may be found in the heel seam of the uppers of ladies' slippers, the work being right side out as the tape is applied.

Another object of the invention is to provide for the arrangement of parts in a device of this kind so that the seam operated upon may be shaped during the application of the tape, thereby eliminating the bulges and puckers which ordinarily occur in a taped seam which must be subsequently shaped and formed.

Another object of the invention is to arrange for the operation of parts so that an operator may tape a complete lot of pieces as rapidly as they can be fed to the machine, the seams being flattened and shaped simultaneously with the application of the tape.

Another object is to provide for the continuous operation of the machine to the end that an entire lot of completed parts such as uppers are properly formed and finished and adhesively secured to a single length of tape, the parts being separated by severing the tape.

These and other objects are attained by the means described herein and disclosed in the accompanying drawings in which:

Fig. 1 is a fragmental vertical sectional view showing the method of taping the seam of a piece of work with the machine of the invention.

Fig. 2 is a front elevational view of a machine of the invention.

Fig. 3 is an end elevational view of the device including an electric tape pre-heating means looking toward the right on Fig. 1 and showing the operating elements in one position.

Fig. 4 is a fragmental end elevation of the operating elements in another position.

Fig. 5 is a perspective view of one of the operating elements.

In the present invention there are presented new and useful improvements in the operating elements in a taping machine which so co-operate as to open new fields of adaptability and improved and increased production methods in the manufacture of shoes.

The invention provides essentially for the application of tape to seams with the work in a

right side out relation so that the normal efforts of the operator in feeding the work to the machine assist the machine to give the desired shape to the work. In Fig. 1 a pair of shoe upper members U are shown stitched together to form a heel seam S held in substantially the position of the desired ultimate shape upon a piece of tape T. The tape has on its upper face adhesive substance in a tacky state. The seam S has the right side up and is being stretched by the normal efforts of the hands of the operator in feeding the work through the machine. 5

The device comprises an upright 19 mounted on a base 11 and having an arm 12 overhanging the base. A shaft 13 is suitably journaled in the arm and it is turned by a suitably driven pulley 14. At one end of shaft 13 is a co-operating cam structure indicated generally as 15, by means of which a hammer rod 16 and a presser foot rod 17 have alternating and substantially vertically reciprocatory movement imparted thereto with great rapidity. The rod 16 is also arranged so that the cam mechanism 15 also swings it rearwardly on the downward movement and returns it on its upward movement. 10

A rotary anvil 18 having its axis set forwardly of the rod 16 upon an axle 19 has a rounded periphery 20. The rod 17 has attached to its depending end a presser foot 21 which is cleft or divided at 22 providing edge pressing portions 23 which are arcuately cut away at 24 complementarily to the rounded anvil face 20. When the rod 17 descends the curved faces 24 of the presser foot 21 engage the anvil above and slightly to the rear of the vertical diameter of the anvil, as may be noted in Figs. 2 and 4. 15

The downward and rearward movement of the presser foot 21 is adapted to impart a smoothing and pressing action upon a tape and the edges of a seam operated upon thereby and also facilitates the manual operation of drawing a piece of work between the anvil and operating parts by the operator. As previously explained the hammer rod 16 has a vertical reciprocation in alternate sequence to that of the presser foot 20 rod 17. A hammer 25 is secured to the hammer rod 16 and operates in the cleft or space 22 of the presser foot. By reference to Figs. 2 and 3 it will be noted that the contacting face 26 of hammer 25 conforms substantially to the peripheral curvature of the anvil 18. A suitably mounted guard 27 is disposed about the front of the anvil 18 and has a top or table portion 28 which is disposed thereabout, or slightly above 25

a tangential position, with relation to the pe- 55

periphery 28 of the anvil. The interior of the guard 27 forms a guide through which an adhesive tape 29 is passed onto the anvil with the adhesive side of the tape up or outwardly of the face of the anvil. As shown in Fig. 3 the adhesive tape 29 is rendered tacky by passing it through an electrically energized tape preheater, diagrammatically shown at 30, through which the tape passes on its way to the guard 27. The preheater may be of any suitable construction, for example as shown in my United States Patent 1,556,124 of October 6, 1925. The material comprising the seam to be taped is passed over the top or table portion 28 beneath the operating members 24 and 25 with the finished side of the material facing upwardly and exposed to the view of the operator. The rough edges of the seam on the unfinished side are thus spread (upon the tape) over the rounded face 29 of the anvil while the hammer 25 effects a series of rapid blows at the center of the seam on the finished side of the material which effectively flatten the seam and thus eliminate a like operation in a separate machine. The machine effects step by step feeding of the work between the rapid series of blows upon the seam and the normal tension exerted upon the seam by the operator will effectively condition the parts to assume substantially the desired ultimate shape. In this way the seam is rendered very flat and the shorter curves, as on the inside of a heel seam have just the necessary length of tape over them so that all tendency to puckering and imperfect adhesion is overcome. Simultaneously with this series of rapid hammer blows the presser foot 24 is reciprocated in alternate sequence with the hammer and this foot spreads and presses the edges of the seam outwardly and rearwardly over the adhesive face of the tape. Where the intended curve of the seam in material operated upon conforms generally to the curve of the top of the anvil the operator merely draws or pushes the work between the anvil and operating members with a slight downward movement. It will be noted from Figs. 2 and 3 that the sides, front and rear of the machine about the anvil and operating members are clear and unobstructed to permit of free manipulation of the work. If the exterior curve of the finished seam is to be convex the operator passes the work between the operating elements and anvil and simultaneously imparts an upward or lifting movement to the material. Where the outward contour of a finished seam is to include both concave and convex portions the operator combines the aforementioned movements of the work as the several curves of the seam approach the operating members. It should be noted however that the material and the seam to be pressed and taped tends to direct the work in the desired direction independently of the manipulation of the operator so that an inexperienced operator may perform perfect work with the machine. The speed of operation of the machine by the operator is limited only by the speed of the operator's movements in feeding seam after seam in successive pieces of work beneath the operating elements. In this way the successive pieces of work follow one another on a single tape with practically no waste of adhesive tape. The tape is severed at the opposite ends of the seam after a lot has been completed. It will be observed that the tape has been stretched and formed both laterally and longitudinally of the seam as it was

applied during the normal rapid feeding of the pieces of work through the machine by the operator.

What is claimed is:

1. In a machine for taping heel seams and the like, the combination of a freely moving arcuate tape receiving anvil, means to direct heat plastic tape thereto, means to preheat the tape to render one face adhesive, said adhesive being exposed when the tape is on the anvil, a work guide over which a shoe upper or the like having a seam to be taped may be directed with the rough side of the seam downward for contacting the tape on the anvil, and means reciprocable onto the smooth side of the seam to spread the seam laterally onto the tape and to direct intermittent blows on the seam, the spreading and hammering action of said means cooperating with the anvil to progressively flatten the seam, spread the tape laterally over the seam and to simultaneously form the work and tape arcuately along the seam. 15

2. In a device for taping curved seams of shoe uppers and the like in a right side out condition comprising a freely rotatable anvil having a transversely arcuate periphery, guide means over which such stitched shoe upper or the like may be directed with a seam right side up for movement over the anvil, means to supply single faced adhesive tape onto the anvil with the adhesive side up whereby the tape may be progressively positioned over the rough side of the seam as the work is manually moved over the anvil, and cooperating reciprocating means operative upon the right side of the work for transversely spreading the work and tape and for directing blows onto the seam as the work is moved over the anvil whereby the tape is caused to adhere to the work for covering the seam and the work is simultaneously formed to the ultimate desired shape. 30

3. In a device for operating upon material having curved edges sewed together to provide an ultimate curved form giving seam comprising a freely rotatable anvil, means to direct tape thereon with the adhesive side up, a work guide permitting the material to be directed progressively onto the tape on the anvil with the seam under mild transverse tension, a presser foot reciprocable onto the outer face of the work on opposite sides of the seam and an alternately reciprocable hammer mechanism for directing blows progressively to the seam intermediate the spreading portions of the presser foot. 45

4. A step by step tape applicator and seam forming device comprising a freely rotatable anvil, means to feed tape onto the anvil and a combined reciprocating presser foot and alternately reciprocating hammer mechanism cooperating therewith to effect lateral spreading and forming of an interposed seam carrying material as said material is progressively fed, right side up over the tape on the anvil and beneath said mechanism. 55

5. In a device of the class described the combination of a freely rotatable anvil member having an arcuate peripheral face, means to direct a tape over the face of the anvil with the adhesive side of the tape uppermost and an alternately reciprocable step by step feed presser foot and hammer mechanism operable toward the anvil for stretching, flattening and shaping seams of work fed therebeneath and simultaneously effecting adhesion and shaping of the tape and the work. 60
